UNITED STATES PATENT OFFICE.

PEDER C. THONER, OF EVERETT, MASSACHUSETTS.

LOCKING-SWITCH.

1,239,062.

Specification of Letters Patent.

Patented Sept. 4, 1917.

Application filed December 2, 1916. Serial No. 134,611.

To all whom it may concern:

Be it known that I, PEDER C. THONER, of Everett, in the county of Middlesex and State of Massachusetts, have invented certain new and useful Improvements in Locking-Switches, of which the following is a specification.

This invention relates to electric switches especially adapted for high voltage circuits. 10 Such switching devices are usually attached to a wall and sometimes to a ceiling, and the opening and closing of the switch is then customarily effected by means of a pole having a hook to engage the movable member of the switch to pull that member open or to swing it back to close the circuit. It is, of course, desirable that there shall be no liability of the switch accidentally opening, due to the effect of gravity 15 or for other reasons.

One of the objects of my invention is to provide improved means for positively locking the movable member of the switch so that it cannot be accidentally thrown. 25 Another object is to provide an improved double-throw switch of this character having simple and compact locking devices.

My invention as a whole comprises an improvement upon, or a carrying forward of, 30 the switch and locking mechanism described and claimed in my application filed October 30, 1914, Ser. No. 869,408.

To this end my invention consists in the improvements which I shall now proceed to 35 describe and claim.

Of the accompanying drawings,

Figure 1 is a side elevation of a double-throw switch having my improved locking means.

40 Fig. 2 represents a section on line 2—2 of Fig. 1.

Fig. 3 is an end elevation from the right of Fig. 1.

Fig. 4 is a detail elevation of one of the 45 locking bars or levers.

Similar reference characters indicate similar parts in all of the views.

Connected to a suitable insulating plate or base 12 are three pairs of jaws 13, 14, 50 15, having any suitable means whereby circuit connections can be made with the stems 16, 17, 18, which respectively extend from the bases of the jaws 13, 14, 15 through the insulating plate 12.

55 The intermediate jaws 14 carry a pin or bolt 19 which serves as the pivot of the

switch blade 20. Adjacent the bases of the other jaws 13, 15, are catch lugs 21, 22, respectively.

The outer end of the blade 20 is formed 60 with an eye 23, and pivotally mounted close to said eye are two locking levers or bars which are duplicates of each other in form and construction and which overlap opposite sides of the blade. One of these levers 65 or bars 24 is pivoted at 25 and has one end formed with a curved wall 26 which is of substantially semi-circular formation and is of shorter radius than the radius of the adjacent wall of the eye 23. Normally the 70 wall 26 is nearer the axial center of eye 23 than the adjacent wall of said eye, for a reason presently explained.

The outer portion of the pivoted bar or lever is in a different plane from that of 75 the portion so far described and at its extremity is hook-shaped, as at 27, to engage catch lug 22 when the blade is swung over from its Fig. 1 position. In other words, the inner portion, having the curved wall, 80 is offset from the plane of the outer portion having the hook, so that while the former overlaps one side of the blade and is pivoted thereto, the latter is in substantially the same plane as the blade as best illustrated 85 in Fig. 3. Said outer portion has two shoulders 28, 29, adapted to limit the movement of the lever in either direction. A spring 30 engaged at one end in a socket 31 in shoulder 29 (Fig. 4) and at the other end 90 bearing against the edge of the blade, serves to hold the lever in position to cause the hook to engage lug 22.

The other lever or bar, being a duplicate of the one just described, has its essential 95 parts indicated by the same reference numerals with the addition of the exponent "a."

When the switch is in the position shown in Fig. 1 and it is desired to open or throw the switch blade, a suitable hook-operating 100 implement indicated by dotted lines at 32 is inserted between the two curved walls 26—26a. Then by a simple downward pull the action is first to swing the lever or bar 24a to the position indicated by dotted lines 105 in Fig. 1. This unlocks the switch. By a further manipulation of the switch blade by means of the operating implement, the blade may be swung over to engage the switch jaws 15, so that when the blade reaches its extreme new position the hook 27 will automatically engage the catch lug 22. This is 110

when my improvements are applied to a double throw switch. Of course a reverse operation of the kind just described will result in returning the switch blade to the position shown in Fig. 1.

For a single throw switch, when a lock is desired to hold the blade when open, the switch jaws 15 would be omitted, the catch lug 22 being, of course, retained for holding the single throw switch in open position.

I do not limit myself to the exact details illustrated and described. For instance, the blade 20 need not be formed with a complete eye 23. This is because the shoulders 15 of the two locking levers or bars which are adapted to contact with the edges of the blade, enable the pull of the operating implement on either one of the pivoted levers or bars to be transmitted to the blade 20 for swinging the blade.

My attachments to the blade are exceedingly simple and compact and are not such as to interfere with the well known type of test clip which is frequently mounted just 25 beyond the end of the blade.

The structure is such that the switch can be attached either to a wall or to a ceiling without alteration, and enable the blade to be unlocked and opened by a downward pull 30 of an operating implement. This is because the inner wall of the curved portion of each of the pivoted bars is of substantially semi-circular formation, and is of shorter radius than the radius of the adjacent wall of the eye 23, when the latter is employed, so that, whether the switch is in 35 vertical or horizontal position, there will always be a portion of said inner curved wall that can be engaged by a hook on the end of 40 an operating pole to cause the release of either hook from its catch lug by a simple downward pull.

Having now described my invention, I claim:

1. An electric switch comprising three posts, a switch blade pivotally connected to the middle of one of the posts, said blade being provided with an opening to be engaged by an operating implement, a catch lug adjacent each of the other posts, switch jaws adjacent each of said catch lugs, a pair of bars pivotally connected to opposite sides

of the blade and projecting in opposite directions therefrom, the outer end of each arm being hook-shaped to engage a catch lug 55 and having its other end overlapping said opening, a spring for each bar to hold it normally in position for its hook to engage a catch lug, each of said overlapping ends having an inner wall curved to a substantially semi-cylindrical form, the said curved wall being nearer the axial center of the opening in the blade than the inner wall of said opening and of shorter radius than the radius of the adjacent wall of said opening, 60 whereby the switch blade may be unlocked and opened by an operating implement inserted in said opening and pulled downwardly, whether the switch is attached to a wall or to a ceiling. 70

2. A locking switch of the character described, comprising a pivoted blade, a contact therefor, a bar pivoted directly to the blade and having one portion provided with a hook in the plane of the blade and having 75 an offset portion adjacent one side of the blade, said offset portion having a curved edge wall to be engaged by an unlocking implement, said bar having two shoulders opposite one edge of the blade to limit the degree of movement of the bar relatively to the 80 blade, and a fixed catch to coöperate with said hook to hold the blade in coöperation with said contact.

3. A locking switch of the character described, comprising a pivoted blade, a contact therefor, a bar pivoted directly to the blade and having one portion provided with a hook in the plane of the blade and having 85 an offset portion adjacent one side of the 90 blade, said offset portion having a curved edge wall to be engaged by an unlocking implement, said bar having two shoulders opposite one edge of the blade to limit the degree of movement of the bar relatively to the 95 blade, a spring interposed between one of said shoulders and the edge of the blade, and a fixed catch to coöperate with said hook to hold the blade in coöperation with said contact. 100

In testimony whereof I have affixed my signature.

PEDER C. THONER.
